TUMBLING MILL

Charles H. Hammell, Mishawaka, Ind., assignor to The American Foundry Equipment Company, Mishawaka, Ind., a corporation of Delaware

Application March 7, 1938, Serial No. 194,309

16 Claims. (Cl. 51—9)

This invention relates to tumbling mills for cleaning and smoothing castings, forgings and the like.

In cleaning, polishing, hardening or otherwise 5 treating small metal articles such as castings, forgings and the like, the process may be carried out in a tumbling mill in which the articles are placed and subjected to the action of projected abrasive particles while the articles are being 10 tumbled.

When a single tumbling barrel is used it has been common practice to charge the articles to be treated into the barrel when the supply of projecting abrasive is shut off. After charging 15 the barrel, the abrasive may be projected with sufficient impact to clean the articles such as castings while they are being tumbled. After the articles have been treated the requisite length of 20 time, the discharge of the treated castings requires shutting off the abrasive supply while the tumbling barrel is being unloaded. It is, therefore, desirable to avoid these shut downs and maintain the abrasive throwing mechanism in 25 operation continuously whereby to do active work without the necessity of relatively long shut downs incident to charging and discharging the tumbling barrel operating on the so-called batch system.

The present invention accomplishes the foregoing 30 desirable end by providing a plurality of pockets or tumbling barrels mounted so as to be capable of being brought successively in and out of the path of abrasive projected at blasting velocities. Provision is made to charge the barrels 35 consecutively at a predetermined position while the barrels which have been charged are receiving abrasive cleaning treatment at another position or positions in the path of travel of the barrels. Simultaneously a barrel containing 40 treated articles may be discharged at another position. Thus, the cleaning or blasting action may be continuous and the time incident to charging and discharging is not spent at the expense of shutting down the abrasive projecting mechanism.

According to one form of the invention, the mill comprises a stationary casing in which is positioned a relatively large conveyor supporting wheel made up of two discs or frames in parallel 50 spaced relation mounted to rotate on a horizontal axis. A continuous conveyor or belt is trained over sprockets mounted in the discs and over rotatable barrel heads also mounted on the discs.

These are arranged to form, in effect, a plurality 55 of tumbling barrels each having rotatable heads

and a movable side wall provided by the conveyor. The tumbling barrels thus formed between the discs are positioned equidistant from each other and radially from the horizontal axis of the wheel formed by the discs. Consequently, the barrels may travel in a circular orbit when the large conveyor supporting wheel rotates on its axis.

Additionally, the conveyor belt may be caused to travel when the large wheel carrying it is stopped for the purpose of tumbling articles in the barrels thus formed when they are in the cleaning position and to assist in discharging cleaned articles from the barrels when the barrels are in the discharging position in their orbit of travel about the common horizontal axis of the large wheel.

The wheel assembly is arranged for step by step rotation, if desired, thus to stop the barrels intermittently at predetermined positions in their orbit of travel. Mounted above the wheel are abrasive throwing devices positioned to project abrasive into one or more of the barrels to clean castings or other articles therein while they are being simultaneously tumbled by the travelling conveyor. Provision is made to charge an empty barrel at another position or station in the orbit while the cleaning operation just mentioned is proceeding. Further provision is made to discharge at the same time treated castings at another station.

Moreover, suitable means are provided for removing the abrasive which has been projected into the mill and for returning it to the abrasive projecting mechanism whereby the abrasive can be used in a continuous cycle.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a view partly in elevation and partly in section of one form of mill according to the invention;

Fig. 2 is a view in cross-section on line 2—2 of Fig. 1;

Fig. 3 is a view in cross-section on line 3—3 of Fig. 2; and

Fig. 4 is a view in part in elevation of one disc of the wheel assembly.

In the following description and in the claims, various details will be identified by specific names for convenience, but they are intended to be as generic in their application as the art will permit. Like reference characters denote like parts in the several figures of the drawings.

Referring to the drawings, the conveyor supporting wheel assembly may be mounted on fixed stationary hollow stub shafts 10 and 11 which may be supported in heavy pedestals 12 and 13 resting on a suitable foundation or heavy cross beams. These hollow shafts are large enough to accommodate a screw conveyor 14. By connecting the inner ends of the stub shafts 10 and 11 which have a common axis with a pan 15 a trough is formed to catch abrasive which may be returned to a feed hopper 16 through suitable conduit and elevator means.

Two side wall members which may be in the form of discs 17 and 18 may be mounted in parallel spaced relation to rotate on suitable bearings which may be roller bearings 19 and 20 positioned at the inner ends respectively of hollow shafts 10 and 11. These side wall members may be connected by shafts 21 and 22, each shaft carrying spaced sprockets 23 and 24 fixed thereto. The assembly forms a conveyor supporting wheel rotatable on a common axis of rotation through the centers of the shafts 10 and 11. Each of the shafts 21 may be provided with a sprocket 29 mounted on the outer side of the side wall member 17. A chain drive 25 (indicated by dot and dash line) is trained over the sprockets 29 and may be driven by a motor 26. An idler 27 may be provided to keep the chain drive 25 taut.

Between the side wall discs 17 and 18 there may be mounted a plurality of pockets or tumbling barrels each of which may comprise a pair of spaced barrel head members 30 and 31 rotatably mounted in journals 32 and 33 in the wheel side walls 17 and 18 respectively. Thus each pair of barrel heads rotate on a common axis. Eight of such pairs of barrel heads are shown although a greater or less number may be desirable in particular cases. It will be apparent from the drawings that the axes of rotation of the respective pairs of barrel heads are equidistant radially from the axis of rotation of the wheel assembly (designated generally by the reference character 28) and they are also equally spaced apart.

To form the side walls of the respective tumbling barrels of which the pairs of barrel heads 30 and 31 constitute the end walls, a single continuous link belt 34 may be trained over the sprockets 23 and 24, and the rotatable barrel heads 30 and 31. Each barrel head may have an annular offset flange 35 on its periphery and each barrel head may have a liner plate 36 removably secured thereto, the liner plate 36 with the offset flange 35 forming a circular groove 37 to accommodate flanges on the link belt 34 to guide the link belt and to provide for rotation of the barrel heads when the conveyor belt is moved linearly; that is, in a direction over the sprockets 23 and 24 and the barrel heads 30 and 31. Arcuate tracks 98 and 99 may be fixed on the side wall discs 17 and 18 to assist in guiding the conveyor belt 34 and to hold the slack. Seal plates 39 and 40 may be provided on the periphery of the wheel as a partial protection to the sprockets 23 and 24 and the conveyor belt chain 75 drives 41 and 42.

The continuous conveyor belt may be of the link type carrying on each side, link sprocket chains 41 and 42 running over sprockets 23 and 24. A suitable construction for such a belt is disclosed in Letters Patent to Louis D. Peik, No. 1,882,443.

From the foregoing description it will be apparent that the continuous conveyor belt, together with the rotating barrel heads form a plurality of individual pockets or tumbling barrels mounted in the wheel assembly as shown generally in Fig. 2.

In order that the wheel assembly 28 may be caused to rotate intermittently or by a step by step movement about its axis of rotation a plurality of lugs 43 (see Fig. 4) may be mounted on the side wall disc 18 in a circular path. A spring pressed stop pin 44, mounted in the side wall 45 of the housing or casing 46, in which the wheel assembly is mounted, may coact with the lugs 43 to stop the movement of the wheel assembly. Thus, when the stop pin 44 is allowed to engage the side wall 18 of the wheel a lug will engage the pin and prevent movement of the wheel assembly. Hence, when the drive chain 25 is driven by the motor 26, sprockets 29 and 22 to rotate with consequent linear movement of the conveyor belt 34. The lugs 43 are spaced to stop the respective tumbling barrels at predetermined stations in the orbit of their revolution about the axis of rotation of the wheel assembly. When the stop pin 44 is pulled out and disengaged from the stop lugs the wheel assembly will rotate because the resistance of the relatively heavy conveyor belt 34 will permit the drive chain 25 to rotate the wheel assembly on the shafts 10 and 11 unless means are provided to stop its rotation.

If desired the stop pin 44 which is manually operated may be dispensed with and other means provided for the rotation step by step of the wheel assembly. An annular gear 47, which may be made of segments, may be fixed to the periphery of the side wall disc 18. This gear may engage a pinion 48 fixed to a shaft 49 driven by a motor 50 connected with a suitable drive 51. An electrical relay and timer (known in the art) for stop, pause and start operation may be connected with the motor 50 and suitable contacts corresponding to lugs 43.

Abrasive projecting mechanism such as one or more centrifugal abrasive throwing wheels 52 and 53 may be mounted in the roof 54 of the housing or casing 46 in such manner as to project abrasive at blast cleaning velocities into the casing and in the path of travel of the tumbling mills or pockets of the wheel assembly. It is preferable to project the abrasive in a downward direction into the tumbling barrels (as shown generally in Fig. 2) for cleaning articles which may be more conveniently tumbled when the curvilinear portions of the segments making up the side walls of the tumbling barrels form the necessary holding pockets. It will be apparent that articles such as castings and forgings in the uppermost barrels will be tumbled when the conveyor belt 34 is caused to move linearly, particularly when the wheel assembly 28 is not in rotating motion.

The stationary hollow shafts 10 and 11 support a suitable pan or trough 15 which catches the major portion of abrasive projected into the uppermost tumbling barrels since the link belt 34 provides ample slots or spaces to permit the used abrasive to fall through into the central trough 75

15. A screw conveyor 14 mounted to rotate in the hollow shafts 10 and 11 carry used abrasive into the elevator shaft 56 through which it may be elevated to the feed hopper 16 through another 5 conveyor 90 and again passed to the abrasive projecting mechanism.

In addition to the central abrasive trough 15 another abrasive collecting trough 57 may be provided in the lower portion of the casing 46. 10 This trough may likewise be provided with a screw conveyor 58 to carry abrasive, projected into the casing and not caught by the central trough 15, into the elevator shaft 56. The two screw conveyors 14 and 58 may be driven by a 15 motor 59 suitably connected by drive chains 60 and 61 over sprockets 62, 63 and 64.

20 Radially disposed baffles 65 may be mounted between the side wall discs 17 and 18 to direct abrasive into the trough 15. Additional baffles 66 and 67 may be fixed to the casing walls to avoid undesirable splattering of the abrasive toward the charging and discharging doors described hereafter.

25 The casing 46 may be provided with a lift type charging door 68 positioned in the side wall 69 of the casing. A charging platform 70 may be fixed to the casing. It facilitates charging articles to be cleaned into the tumbling barrel opposite the charging door 68.

30 A discharge opening 71 having a discharge chute 72 may be provided in the opposite side wall 73 of the casing. It will be apparent that articles in the tumbling barrel opposite this discharge opening will be carried out of the barrel 35 into the chute when the conveyor belt 34 is caused to move linearly in the direction of the arrow 14.

Operation

The tumbling mill may be operated as follows: 40 The wheel assembly may be adjusted to take the position shown generally in Fig. 2. The abrasive conveyors 14, 58 and 90 together with the necessary elevator in shaft 56 are placed in operation. The tumbling barrel opposite charging door 68 is charged with a suitable quantity of 45 articles, such as small castings 100. The conveyor belt 34 is placed in operation. The wheel assembly may then be caused to rotate a step in the direction of the arrow 29a so as to bring the charged barrel under the centrifugal abrasive throwing wheel 52 which is placed in operation. The next successive barrel is charged through the 50 charging door while the articles 100 are being subjected to the projected abrasive. The wheel assembly is then caused to rotate another step thus to bring the first charged barrel under the 55 abrasive throwing wheel 53 which is placed in operation.

While the castings in the barrels beneath the 60 throwing wheels are being tumbled by reason of the linear movement of the conveyor belt 34 and simultaneously subjected to the projected abrasive, the next successive barrel is being charged through the charging door 68.

65 After the articles are given the requisite cleaning by the abrasive projected by the throwing wheels, the conveyor supporting wheel assembly is caused to move another step, thus bringing a barrel containing cleaned castings opposite the discharge chute 72 and at the same time an empty barrel opposite the charging port 68.

It will be observed that the barrel opposite the discharge chute takes a position which is analogous to tipping the barrel and the cleaned articles 70 are carried out by the linearly travelling con-

veyor belt 34. While the cleaned castings are thus being discharged, uncleared castings may be charged into a barrel opposite the charging door 68, and simultaneously the castings in the barrels beneath the throwing wheels are being cleaned. The operation may be carried on continuously step by step without the necessity of stopping the flow of projected abrasive which is returned and recycled through the throwing 10 wheels.

Thus, a continuously operating tumbling mill may be provided which will effect great savings in time incident to cleaning as compared with a cleaning apparatus wherein a single barrel only is used, there being, according to the invention, no 15 necessity for the throwing wheels to remain idle at any time during the operation of the continuous mill.

20 While certain novel features of the invention have been disclosed and are pointed out in the annexed claims, it will be understood that various omissions, substitutions and changes may be made by those skilled in the art without departing from the spirit of the invention.

What is claimed is:

25 1. In apparatus of the character described, a conveyor supporting wheel mounted to rotate about an axis, means mounted on said wheel to train a conveyor belt, a conveyor belt trained by the aforesaid means to form a plurality of tumbling barrels disposed about the axis of rotation of said wheel, means to move said conveyor belt along the path of travel provided by said training means, and means to rotate said wheel about its axis of rotation whereby to revolve said barrels in an orbit about said axis of rotation.

30 2. In apparatus of the character described, a conveyor supporting wheel comprising spaced apart side frames mounted to rotate about a common axis, means including discs spaced apart 35 mounted on said side walls to train a conveyor, a continuous conveyor trained by said means to form a plurality of tumbling barrels revoluble in an orbit about the axis of rotation of said wheel, means mounted on said wheel to move said conveyor along the path of travel provided by said training means, and means to rotate said wheel whereby to revolve said barrels in said orbit about the axis of rotation of said wheel.

35 3. In apparatus of the character described, a 40 stationary casing, a conveyor supporting wheel comprising side walls spaced apart in parallel relation mounted to rotate within said casing about a common axis, means including discs spaced apart in parallel relation and rotatable 45 about another axis of rotation to train a conveyor, a continuous link conveyor trained in part by said rotatable discs to form a plurality of tumbling barrels revoluble about the axis of rotation of said wheel, means mounted on said wheel to move said conveyor linearly along the path of travel provided by said training means, and means to rotate said wheel step by step to revolve said barrels intermittently in an orbit about the 50 axis of rotation of said wheel.

4. In apparatus of the character described, a conveyor, means for training said conveyor to form a plurality of tumbling pockets, projecting mechanism to discharge abrasive at blasting velocities, means for moving said pockets into and 55 out of the path of abrasive discharged from said projecting mechanism, and means to move said conveyor to tumble articles within said pockets when in the path of abrasive discharged at blasting velocity from said projecting mechanism.

65

75

5. In apparatus of the character described, a conveyor belt, means including rotatable barrel heads for training said conveyor to form a plurality of tumbling barrels, projecting mechanism to discharge abrasive at blasting velocities, means for moving said barrels in an orbit into and out of the path of abrasive discharged from said projecting mechanism, and means to move said conveyor belt to tumble articles within said barrels
10. when in the path of abrasive discharged at blasting velocity from said projecting mechanism.
6. In apparatus of the character described, a link belt movable linearly, means including rotatable barrel heads mounted on a rotatable frame for training said conveyor to form a plurality of tumbling barrels on said rotatable frame, means for moving said barrels in an orbit about the axis of rotation of said frame, and means to move said belt linearly to tumble articles within said barrels when in the path of abrasive discharged at blasting velocity on to said articles.
7. In apparatus of the character described, a conveyor, means for training said conveyor to form a plurality of tumbling pockets, projecting mechanism comprising a centrifugal blasting wheel to discharge abrasive at blasting velocities, means for moving said pockets into and out of the path of abrasive discharged from said blasting wheel, means to move said conveyor to tumble articles within said pockets when in the path of abrasive discharged at blasting velocity from said blasting wheel, and means to return used abrasive to said blasting wheel.
8. In a tumbling mill, a frame rotatable on an axis, a plurality of receptacles mounted on said frame revoluble in an arc about the axis of rotation of said frame, each of said receptacles including a belt movable in a curvilinear direction to tumble articles therein, mechanism for projecting abrasive at blasting velocity, means for moving said receptacles in said arc into and out of the path of abrasive projected at blasting velocity from said mechanism, and means to move said belt to tumble articles within a receptacle when it is in the path of projected abrasive.
9. Apparatus for blast cleaning metallic articles including, a frame rotatable on an axis, a plurality of tumbling barrels mounted on said frame revoluble in an arc about the axis of rotation of said frame, each of said barrels including rotatable barrel heads and a belt movable in a curvilinear direction about the periphery of said barrel heads to tumble articles therein, mechanism for projecting abrasive at blasting velocity, means for moving said barrels in said arc into and out of the path of abrasive projected at blasting velocity from said mechanism, and means to move said belt linearly when a receptacle is in the path of projected abrasive.
10. A tumbling mill comprising, a casing, a frame within said casing rotatable on an axis, a plurality of tumbling barrels mounted on said frame revoluble in an orbit about the axis of rotation of said frame, each of said barrels including a pair of rotatable barrel heads and a movable belt trained over said barrel heads, means for moving said barrels step by step in said orbit to bring each barrel successively into abrasive cleaning position, and means to move said belt linearly whereby to cause articles in said barrel to be tumbled when in said blast cleaning position.
11. A tumbling mill comprising, a casing, a barrel supporting wheel within said casing having side wall members spaced apart in parallel spaced
- relation and mounted to rotate on hollow shafts having a common axis of rotation, a plurality of tumbling barrels mounted between said side wall members, said tumbling barrels being movable with said side wall members to revolve said barrels in an arc about the axis of rotation of said shafts, an abrasive moving member mounted within said hollow shafts to carry abrasive from said casing, and a second abrasive moving member positioned in the lower portion of said casing to carry abrasive therefrom.
12. A tumbling mill comprising, a casing, a barrel supporting wheel within said casing having side wall discs spaced apart in parallel spaced relation and mounted to rotate on hollow shafts having a common axis of rotation, a plurality of tumbling barrels having rotatable end members mounted between said side wall discs, said tumbling barrels being movable with said side wall discs to revolve said barrels in an arc about the axis of rotation of said shafts, and a screw conveyor mounted within said hollow shafts to carry abrasive from said casing.
13. A tumbling mill comprising, a casing, a barrel supporting wheel within said casing having side wall members spaced apart in parallel spaced relation and mounted to rotate on hollow shafts having a common axis of rotation, a plurality of tumbling barrels each having rotatable heads and a curvilinear side wall which constitutes a part of a continuous belt mounted between said side wall members, said tumbling barrels being movable with said side wall members to revolve said barrels in an arc about the axis of rotation of said shafts, a screw conveyor mounted within said hollow shafts to carry abrasive from said casing, and a second screw conveyor positioned in the lower portion of said casing to carry abrasive therefrom.
14. A tumbling mill which comprises, a casing, means to project abrasive at blasting velocity into said casing, two side wall discs in parallel spaced relation mounted to form a wheel within said casing rotatable on a common axis, a hollow shaft to carry said wheel, a plurality of pairs of barrel head members mounted between said side wall discs, each pair of barrel head members being rotatable on a common axis through their centers, a screw conveyor operable within said hollow shaft to remove abrasive from said casing, rotatable shafts carrying sprockets connecting said side wall discs, a conveyor belt trained over said sprockets and rotatable barrel head members to form a plurality of tumbling barrels equally spaced apart and revoluble in an orbit about the axis of rotation of said wheel, means to rotate said sprockets thereby to cause said conveyor belt to move linearly, and means including a segment gear to rotate said wheel step by step about said hollow shaft to bring each barrel successively into the path of projected abrasive.
15. A tumbling mill which comprises, means to project abrasive at blasting velocity, two side wall discs in parallel spaced relation mounted to form a wheel rotatable on a common axis, a plurality of pairs of barrel head members mounted between said side wall discs, each pair of barrel head members being rotatable on a common axis through their centers, the axis of rotation of each pair of barrel head members being the same distance radially from the axis of rotation of said wheel and equidistant from each other, an arcuate guide track mounted on said discs adjacent each of said barrel head members, ro-

tatable shafts carrying sprockets connecting said side wall discs, a continuous conveyor belt trained over said sprockets and rotatable barrel head members and riding on said tracks thereby to 5 form a plurality of tumbling barrels equally spaced apart and revoluble in an orbit about the axis of rotation of said wheel, means to rotate said sprockets thereby to cause said conveyor belt to move linearly, means to rotate said wheel 10 step by step to bring each barrel successively into the path of projected abrasive, and means for returning projected abrasive to said abrasive projecting means.

16. A tumbling mill which comprises, means to 15 project abrasive at blasting velocity, two side wall discs in parallel spaced relation mounted to form a wheel rotatable on hollow shafts, a plurality of pairs of barrel head members mounted between said side wall discs, each pair of barrel head 20 members being rotatable on a common axis through their centers, the axis of rotation of

each pair of barrel head members being the same distance radially from the axis of rotation of said wheel and equidistant from each other, an arcuate guide track mounted on said discs adjacent each of said barrel head members, a screw conveyor operable within said hollow shafts to carry abrasive therefrom, rotatable shafts carrying sprockets connecting said side wall discs, a conveyor belt trained over said sprockets and rotatable barrel head members and riding on said 10 tracks thereby to form a plurality of tumbling barrels equally spaced apart and revoluble in an orbit about the axis of rotation of said wheel, means to rotate said sprockets thereby to cause said conveyor belt to move linearly, means to 15 rotate said wheel step by step to bring each barrel successively into the path of projected abrasive, and a second screw conveyor for returning projected abrasive to said abrasive projecting means.

20

CHARLES H. HAMMELL.
